UNITED STATES PATENT OFFICE.

FRANK SPAULDING, OF PROVIDENCE, RHODE ISLAND, ASSIGNOR TO THE BROWN & SHARPE MANUFACTURING COMPANY, OF SAME PLACE.

ADJUSTABLE ANVIL FOR MICROMETER-GAGES.

SPECIFICATION forming part of Letters Patent No. 332,118, dated December 8, 1885.

Application filed April 9, 1885. Serial No. 161,642. (No model.)

To all whom it may concern:

Be it known that I, FRANK SPAULDING, of the city and county of Providence, and State of Rhode Island, have invented a new and useful Improvement in Micrometer-Calipers, of which the following is a full, clear, and exact description, reference being had to the accompanying drawings, forming a part of this specification.

10 My invention relates to the adjustable anvils of all kinds of micrometer-calipers; and the object of my invention is to avoid a certain defect in such anvils as heretofore constructed.

15 The purpose of adjustable anvils for micrometer-calipers is to compensate for wear in the instrument so as to maintain the zero position of the sliding scale. This has heretofore been attempted by the use of an adjustable anvil which rotates throughout its entire 20 length, so that the anvil-face is varied in position with every adjustment.

It has been found very difficult to construct these adjustable anvils with absolutely true anvil-faces and such imperfection, together 25 with the effect of wear upon the anvil-face, has rendered the accurate adjustment of the implement exceedingly difficult if not impossible. In order to overcome this defect, I construct the adjustable anvils in two parts, one 30 of which, the face part, has only a simple sliding movement, while the other, the screw part, turns and works in the screw-thread. Thus the anvil-face preserves at all times its original position, and if there be any defect in 35 its construction such defect may be readily and accurately compensated for.

In order that my invention may be fully understood, I will proceed to describe it with reference to the accompanying drawings, in 40 which—

Figure 1 is a side elevation of a micrometer-caliper with my improvement applied. Fig. 2 is a sectional view of the adjustable anvil and the contiguous part of the caliper-frame. 45 Figs. 3, 4, and 5 are similar views showing modified arrangements of the adjustable anvil.

In the said drawings, Fig. 1, A designates the caliper-frame, which is U-shaped, having the two arms a' , upon the former of which 50 is mounted a screw-stem, B, threaded through a hollow shank, c, having a scale upon its side. D designates a hollow cap secured rig-

idly upon the outer end of stem B and working over the shank c, the inner end of said cap being beveled and carrying a scale upon 55 its beveled portion, which scale works in conjunction with the scale upon shank c in the usual manner.

The frame and the stem, shank, and cap may be either of the precise form and arrangement shown, or of any other suitable or preferred form.

Upon the opposite arm a' of the frame A is mounted my improved adjustable anvil, which consists of a sliding portion or face part, E, and 60 a rotating portion or screw part, E'. The rotating portion E' serves to advance or recede the sliding portion E in the socket of arm a' . In Fig. 2 this result is accomplished as follows: The inner end of the face part E is 65 formed with a longitudinal socket, f, having an internal left-hand screw-thread, while the inner end of screw part E' is formed with a reduced stem, g, having an external left-hand thread. Through a portion of its length from its outer 70 end the socket in arm a' is formed with an internal right-hand thread, while the outer surface of the screw part E' is formed with an external right-hand thread. A longitudinal 75 groove, h, is formed upon the outer side of 80 face part E, and in this groove works a screw-pin, h', which is let into the arm a' from above. Thus when the screw part E' is turned in one direction the face part E will be forced out of 85 the socket, and when the screw part is turned in the opposite direction the face part will be drawn into the socket, the movements of the face part being performed without its turning, as the opposite screw-threads neutralize each 90 other in this respect.

In Fig. 3 the socket f, stem g, and their screw-threads are employed as in Fig. 2; but the groove h and pin h' are dispensed with, the face part E being accurately fitted in the socket of arm a' , so that any possible tendency 95 toward turning in the face part E will be prevented by frictional contact between the face part and the socket. In Fig. 4 the groove h and pin h' are used, as in Fig. 2; but in lieu of the socket f and stem g the inner end of face part E is formed with a circular T-shaped extension, i, which works in a corresponding socket, i', in the inner end of screw part E'. In Fig. 5 the arrangement is the same as in 100

Fig. 4, excepting that the groove *h* is formed in the socket in arm *a'*, while the pin *h'* is inserted into face part *E*. In all of these arrangements it will be seen that while the 5 screw-part *E'* turns the face part *E* merely slides without any turning movement. Hence if there be any imperfection in the face or outer end of face part *E* such defect will not be constantly varying in position as the adjustable anvil is manipulated to take up wear.

Having thus described my invention, I claim as new and desire to secure by Letters Patent—

1. The combination, with the arm having 15 the graduated shank and sliding scale portions, of the co-operating socketed arm provided with an adjustable anvil consisting of a face part longitudinally operated in said socket by a screw part connected to said face part 20 and taking into said socket, for the purpose described.

2. The combination, with the arm having the graduated shank and sliding scale portions, of the co-operating socketed arm provided with an adjustable anvil consisting of a 25 slotted face part longitudinally operated in said socket by a screw part connected to said face part and taking into said socket having therein a guide-piece, for the purpose described.

3. A micrometer-caliper having a socketed 30 arm provided with an adjustable anvil consisting of a face part longitudinally operated in said socket by a screw part having two different diameters reversely screw-threaded, the

part having one diameter taking into said socket, and the part having the other diameter taking into said face part, for the purpose described.

4. A micrometer-caliper having a socketed 40 arm provided with an adjustable anvil consisting of a slotted face part longitudinally operated in said socket, which is provided with a guide-piece, and of a screw part having two different diameters reversely screw-threaded, the part having one diameter taking into the said socket, and the part having the other diameter taking into the said face part, 45 all for the purpose described.

5. The combination, with the arm *a*, bearing 50 the graduated shank *c*, incasing the stem *B*, which has the scaled sleeve *D*, of the arm *a'*, having the anvil-face part *E*, connected to the anvil screw part *E'*, for the purpose described.

6. The combination, with the socketed arm 55 *a'*, of the anvil-face part *E*, connected to the anvil screw part *E'*, which has the reversely-screw-threaded diminished portion *g*, for the purpose described.

7. The combination, with the socketed arm 60 *a'*, having the guide-piece *h'*, of the anvil-face part *E*, having the slot *h*, and connected to the anvil screw part *E'*, which has the reversely-screw-threaded diminished portion *g*, for the purpose described.

FRANK SPAULDING.
